Patented Oct. 22, 1918.

UNITED STATES PATENT OFFICE.

JAMES B. WEIR, OF NEW YORK, N. Y.

METHOD OF MANUFACTURING GASOLENE.

1,282,338.

Specification of Letters Patent. Patented Oct. 22, 1918.

Application filed April 11, 1918. Serial No. 228,036.

To all whom it may concern:

Be it known that I, JAMES B. WEIR, a citizen of the United States, a resident of New York, in the county of New York and State 5 of New York, and a temporary resident of Charleston, in the county of Kanawha and State of West Virginia, have made a new and useful Invention in Method of Manufacturing Gasolene, of which the following 10 is a specification.

This invention relates to a method and apparatus for the extraction of gasoline from natural gas.

At the present time there are several 15 methods utilized for the extraction of gasoline from natural gas. One method which has been commonly used consists in compressing the gas, which either flows from the wells under pressure or is removed from 20 the wells by means of pumps, in a two stage compressor equipped with a suitable inter-cooler, then in passing the compressed gas (compressed to about 250 pounds) through a cooler or condenser where the gas is cooled 25 and the gasoline condensed to liquid form, then passing the compressed and cooled gas and liquid gasoline through a drip which separates the gasoline (the condensate) from the gas. The condensate is passed to 30 weathering or storage tanks and the gas either passes to the gas main or is utilized on the property as a fuel for gas engines or the like.

If, in the final stage of compression the 35 gas is raised to 250 lbs. or more, it has been found that the weathering process is necessary to reduce the vapor tension to a point where the railroads will handle the product in tank cars. In some cases it is now common to blend this condensate with naphtha 40 before weathering. The standard set by the railroads requires a vapor tension of not more than ten pounds at 100° Fahrenheit. The weathering is either done in an open 45 tank by normal evaporation or evaporation is facilitated by passing steam through the product thus driving off the higher or more volatile fractions which cause the excessive vapor tension.

50 If the final compression is not above 70 to 80 lbs. the lighter or more volatile fractions are not liquefied and of course the product condensed from the gas will not require as much weathering, since the vapor 55 tension will be less than where the more

volatile fractions are condensed and contained in the liquefied product.

Another method of extracting gasoline from natural gas has been by one or more of the absorption methods. One of these methods commonly used consists in passing the gas on its way from the wells to the main line through receptacles containing an absorbent menstruum in the form of a relatively heavy oil capable of absorbing a proportion at least of the gasoline content of the natural gas. After the menstruum has become saturated the gasoline is distilled off and the menstruum used over again in the receptacles. Still another method has 60 been to subject the natural gas under pressure to the action of an absorbent such as naphtha, whereby the naphtha takes up from the gas a proportion at least of the gasoline content thereof whereby the volume of the liquid is 65 increased and its gravity raised.

With all of the methods with which I am familiar where relatively high pressures are utilized it is necessary to weather the product. In weathering, the losses range from 70 20 to 50%, that is, the product shrinks in volume from 20 to 50%.

I believe that in the weathering process whether it is accomplished by steaming, which is now the ordinary way of weathering, or by normal evaporation, a certain amount of the lower fractions of the product which at atmospheric pressure and temperature would be a stable liquid are carried away with the lighter or more volatile 80 fractions and in this way lost.

An object of this invention is to provide a method of gasoline manufacture from natural gas whereby the yield of gasoline is increased and the losses heretofore encountered materially reduced. My method broadly consists of three distinct steps so combined and correlated that substantially all of the content of the natural gas is recovered which at atmospheric pressure and 90 temperature is liquid.

In practising my process, the gas as it issues from the wells is passed to a two stage compressor, the first stage of which preferably raises the pressure of the gas to 105 70 lbs. from which it is passed through an intercooler to a second stage where it is preferably compressed up to 250 lbs. From the second stage of the compressor the gas passes through a condenser prefer- 110

- ably consisting of a coil of pipes immersed in a tank of cold water (55° F.). At the outlet of the condenser the gas passes through an accumulating tank, which separates the liquid gasolene from the gas, then the gasolene is taken from the tank into a trap, which works automatically, and the gasolene is discharged into a closed storage tank.
- 10 The gas now partially denuded is passed through an absorption apparatus which consists of a number (preferably 10) of 12" pipes about 25' long arranged horizontally in a vertical tier. Extending lengthwise of 15 each of these 12" pipes is a 2" pipe arranged near the bottom. The inner end of each 2" pipe is capped and perforated along its bottom with 1/16" holes spaced about 1 1/2" apart. The 12" pipes are interconnected for gas passage in such a manner that 20 the gas after it issues from the 2" pipe in the lowermost 12" pipe and after passing up through the base material or liquid therein passes out of the top of the 12" pipe 25 to the 2" pipe next above and so on through the series comprised in the tier. An absorbent base which may either be refinery naphtha or kerosene is pumped into the upper 12" pipe against the gas pressure there- 30 in (250 lbs.). A liquid overflow is arranged within each of the 12" pipes (which are interconnected for the passage of liquid) so that each 12" pipe is always about two-thirds filled with the base liquid.
- 35 The apparatus is arranged so that the partially denuded gas from the condenser continuously passes through the 12" pipes in series and at a pressure of 250 lbs. and so that the naphtha or kerosene base which 40 is pumped into the uppermost 12" pipe passes down through the 12" pipes in series and out of the lowermost pipe, from which point it is forced to the storage tank containing the gasolene derived by compression 45 and cooling. The gas in passing through the 1/16" holes in the 2" pipes is broken up into fine streams and is thus caused to intimately mix with the base liquid. The system is so proportioned and arranged that 50 about one million feet of gas passes through the 12" pipes in every 24 hrs. The apparatus composed of the 12" pipes when each is filled to the proper level contains about 1,200 gallons of menstruum or base 55 liquid and the gas flows therethrough at the rate of one million feet in every 24 hours. The menstruum or base is pumped into the top of the 12" apparatus at the rate of 800 gallons in every 24 hours.
- 60 As the complete plant consists of a number of these 12" apparatus depending upon the amount of gas utilized it has been found preferable to pump into one of them 50 gallons of the base at a time then to shift to 65 the next and so on leaving an interval be-

tween each pumping. If it is desired however the base may be continuously pumped into the 12" apparatus at the rate of about 800 gallons in every 24 hours.

The gasolene derived from the compression and cooling process runs from 88 to 90° Baumé and the product from the 12" apparatus (kerosene 47° Baumé plus gasolene) runs from 58 to 60° Baumé. These two products are mixed in the storage tank before referred to in the proportion of about one-third of gasolene (derived from compression and cooling) and two-thirds of product derived from the 12" apparatus. The product from the storage tank which runs about 70° Baumé and which has a relatively high vapor tension must be reduced to about 64 1/2° Baumé before it will be handled by the railroads. The product therefore is run into a storage or weathering tank, and this is preferably a horizontal tank adapted to withstand relatively high pressures and is there steamed. The steam is led into the bottom of the steaming tank through a 2" pipe which extends from end to end thereof and which is provided with 1/16" holes so that an intimate mixture of the steam and gasolene is obtained. The gasolene is steamed until the proper gravity and vapor tension is obtained (10 lbs. at 100° F.). The vapors arising from the gasolene during the steaming operation are conducted from the top of the steaming tank to a 2" pipe which runs lengthwise in the bottom of a storage fortifying-tank containing either naphtha or kerosene, the base with which I start the process.

I have found that by passing these vapors from the steaming tank and intimately mixing them with the kerosene or naphtha base I can increase the gallonage of the base 10% and raise its gravity 4 1/2° and this which I term a fortified base is the liquid which I pump through the 12" apparatus as a base or menstruum. If desired the vapor from the fortifying tank may be led to the bottom of a second fortifying tank containing base material although I find that if the first fortifying tank contains a sufficient quantity of the untreated kerosene or naphtha, this second tank is not necessary.

The process is a continuous one after being set in operation and it will be seen that the only losses, if they can be called losses, are the vapors derived from the natural gas which are not liquid at atmospheric pressure and temperature. I have found that the ultimate gain due to this process over the process in which the high degree light gasolene is blended with naphtha in the usual way or in which the vapors due to weathering are allowed to escape is approximately 10 to 15% in gallonage with a gain in gravity of 4 1/2° to 5° and, since this gain in gallonage in my plant using two

million feet of gas averages a thousand gallons every 24 hours it will be seen that the saving is extremely important.

The product from the 12" apparatus 5 flows away to the storage tank in proportion to the amount of base added thereto plus the amount of gasoline absorbed from the gas passing through the apparatus.

In the drawings the figure schematically 10 represents a complete plant for carrying out my process.

In practising the process gas from the wells enters line 4, is compressed to about 70 pounds by low stage compressor 5, passes 15 through an inter-cooler 6 and has its pressure raised to about 250 pounds in the high pressure compressor 7. From the high pressure cylinder the gas passes through a condenser 8 which consists of a coil of pipes 20 immersed in water maintained at approximately 55° F. From the condenser the gas passes through a separator 9 which separates the condensate from the gas. The condensate which is a gasoline of about 88 to 25 90° Baumé passes by means of line 10 through a trap 11 and is collected in a mixing tank 12.

The partially denuded gas passes from separator 9 through line 13 to the absorber 30 apparatus 14 consisting of ten 12" headers as shown in Figure 1.

The absorber apparatus consists of a number of 12" horizontal headers arranged in a vertical tier. Extending lengthwise 35 within each header and near the bottom thereof is a 2" pipe capped at its inner end 16 and along its bottom drilled with 1/16" holes spaced about 1 1/2" apart. The headers are interconnected by means of pipes so 40 that the base material (kerosene or naphtha) flows downwardly from the uppermost header 20 through the series against the gas which passes up through the series and for the passage of which the headers 45 are interconnected by means of pipes. The connections between the headers for the passage of the base liquid are so arranged as to maintain a constant level of liquid in each header, or so that each header is always about two-thirds filled with liquid. 50 The gas connections from one header to the next are arranged so that a trap is provided, the upper portion of which extends above the liquid level so that the liquid, when the 55 flow of gas is cut off, will not flow through the gas connections.

The gas entering the lowermost header of the absorber apparatus passes into the base material contained therein (which is preferably kerosene having a gravity of 47 or thereabouts) is broken up by passing through the 1/16" holes. The gas after being minutely broken up and intimately mixed with the base material in the lowermost header 65 issues therefrom through a pipe 17 and

passes into 2" pipe 18 arranged in the bottom of the 12" header next above and this process is carried out throughout the series comprised in the apparatus.

The base material is pumped, by means of 70 a liquid pump 19, into the uppermost 12" header 20 through a line 21 and overflows from header 20 through an upturned L 22 and pipe 23 into the next header located therebeneath. The base liquid flowing out 75 from the lowermost header 14 through pipe 24 flows into mixing tank 12 and mixes therein with the high grade gasoline derived by compression and cooling.

The mixture from the mixing tank 12, 80 by means of a pump 25 is forced into a steam weathering tank 26. Live steam from a suitable source of steam supply such as a gas fired boiler is led through a pipe 27 and caused to issue through perforations in a 85 pipe or coil 28 within the bottom of the tank. In this way the lighter volatiles or higher fractions of the mixed or blended product within the steam tank are driven off. These are conducted by means of a pipe 29 into a 90 fortifying tank 30 containing raw or untreated base material such as kerosene. The fortifying tank is provided in its bottom with a perforated pipe 31 through which the vapors driven off from the product with- 95 in tank 26 are caused to pass by the pressure in the steaming tank into the liquid in tank 30. The liquid in the fortifying tank by this means absorbs the high volatiles. If it is desired, the vapors arising in tank 30, 100 which are ordinarily vented through vent 30a to the atmosphere, may be carried to a second fortifying tank similar to tank 30, or may be caught and compressed to form liquid gas or used as fuel under the steam generator and for that purpose collected in a 105 gasometer.

The fortified base from tank 30 passes by means of pipe 32 to pump 19 which forces it into the upper 12" header against the 110 pressure of the gas therein. The kerosene is stored in a tank 33 and from this tank by means of a line 34 flows into fortifying tank 30. The finished gasoline is withdrawn from steam weathering tank 26 through pipe 115 35 and stored in storage tank 36.

The lean gas after it leaves the uppermost 12" header of the absorber passes through line 37 to a separator 38 and from the separator which separates out any liquids contained in the gas the gas passes through pipe 39 to the main or point of consumption.

Having thus described my invention what I claim is—

1. The method of manufacturing gasoline, 125 which consists in extracting gasoline from natural gas by compression and cooling, in subjecting the partially denuded gas to an absorption step, in blending the products thus derived, in reducing the vapor tension 130

of the blended product by driving off a portion of the more volatile constituents thereof to obtain the finished product, then in absorbing a portion of such volatile constituents in a hydrocarbon liquid heavier than gasolene and in utilizing this product as the absorbent for the absorption step.

2. The method of manufacturing gasolene, which consists in reducing the vapor tension 10 of a hydrocarbon liquid by liberating a portion of its lighter fractions, in fortifying a hydrocarbon liquid heavier than gasolene with such lighter fractions, in passing natural gas through said fortified liquid and 15 then in blending such liquid with high grade gasolene.

3. The method of manufacturing gasolene, which consists in liberating a portion of the lighter fractions of a hydrocarbon liquid by 20 means of heat, in absorbing a portion of such lighter fractions in a hydrocarbon liquid heavier than gasolene, in passing natural gas through such liquid and then in blending such liquid with high grade gasolene.

4. The method of manufacturing gasolene, which consists in steaming a hydrocarbon liquid thereby driving off a portion of its lighter fractions, in passing such lighter fractions through a hydrocarbon liquid 30 heavier than gasolene, then in passing natural gas through such liquid and then in blending such liquid with high grade gasolene.

5. The method of manufacturing gasolene, which consists in compressing and cooling 35 natural gas containing gasolene, in separating the gasolene from the gas and storing the same, in passing the partially denuded gas under pressure through a liquid heavier than gasolene, in mixing such liquid with the gasolene derived by compression and cooling, in steaming such mixture, in liberating the lighter fractions from such mixture then in passing such lighter fractions 45 through a liquid hydrocarbon heavier than gasolene.

6. The method of manufacturing gasolene which consists in compressing and cooling gas containing gasolene, in separating the 50 gasolene thus derived from the gas and storing the same, in breaking up the partially denuded gas and passing the same under pressure through an absorbent base material whereby gasolene is absorbed from such gas, in mixing such base material with the gasolene derived by compression and cooling, in steaming such mixture, then passing the vapors driven from such mixture during the 55 steaming thereof into and through a liquid hydrocarbon heavier than gasolene.

7. The method of manufacturing gasolene, which consists in compressing and cooling gas containing gasolene, in separating the

gasolene thus derived from the gas and storing the same, in breaking up the partially denuded gas and passing the same under pressure through an absorbent base material whereby gasolene is absorbed from such gas, in mixing such base material with the gasolene derived by compression and cooling, in 70 weathering such mixture then passing the vapors liberated from such mixture during weathering into and through a liquid hydrocarbon heavier than gasolene and in utilizing such hydrocarbon liquid after its gravity 75 has been raised by the absorption of such vapors as the base material in the absorption step.

8. The method of manufacturing gasolene, which consists in compressing and cooling 80 gas containing gasolene, in separating the gasolene thus derived from the gas and collecting the same, in finely dividing the partially denuded gas and passing the same under pressure through an absorbent base material whereby gasolene is absorbed from such gas, in mixing such base material with the gasolene derived by compression and cooling, in steaming such mixture to form the finished product, then in absorbing a portion of the vapors driven off from such mixture during the steaming thereof in a hydrocarbon liquid heavier than gasolene and in utilizing such hydrocarbon liquid as the base 90 material in the absorption step. 95

9. That step in the art of manufacturing liquid fuel which consists in reducing the vapor tension of relatively high grade gasolene by steaming the same and in passing the vapors driven off during the steaming 100 thereof through a liquid hydrocarbon heavier than gasolene whereby its gallonage is increased and its gravity on the Baumé scale raised.

10. The method of manufacturing gasolene, which consists in steaming a hydrocarbon liquid thereby liberating a portion of its lighter fractions, in passing such lighter fractions through a hydrocarbon liquid heavier than gasolene and in passing natural 110 gas containing gasolene through such heavier hydrocarbon liquid.

11. That step in the art of manufacturing liquid fuel which consists in reducing the vapor tension of hydrocarbon liquid of relatively high gravity on the Baumé scale and in passing the released vapors through a liquid hydrocarbon of heavier gravity on the Baumé scale whereby the gallonage of the latter is increased and its gravity on the 120 Baumé scale raised.

In testimony whereof, I have hereunto subscribed my name this 2d day of April, 1918.

JAMES B. WEIR.
